UNITED STATES PATENT OFFICE

SYLVAN M. STRAUS, OF GLOVERSVILLE, NEW YORK

MECHANISM FOR CONNECTING PIECES OF MATERIAL

Application filed April 19, 1929. Serial No. 356,583.

My invention relates to a new and improved method of and mechanism for affixing the slit reinforcement and the button reinforcement to a glove blank.

5 One of the objects of my invention is to provide a method whereby the above mentioned reinforcements or either of them can be connected to a glove blank (which is called a "trunk" by the trade), so as to prevent the adhesive from spreading beyond the edges of the reinforcement to spoil the blank.

Another object of my invention is to provide a mechanism whereby the tapes which are utilized for forming said reinforcements 15 are automatically cut into pieces of proper size, and adhesive is suitably and automatically applied to the severed pieces of tape.

Another object of my invention is to provide a machine whereby the piece of severed 20 tape to which adhesive has been applied, is applied by means of air pressure to the trunk or other object. It is to be understood that while my invention is useful in connection with forming glove blanks or "trunks", that 25 said invention is not to be restricted to this particular purpose as it is useful in a great many other fields in which it is desired to connect one piece of material to another, as by means of an adhesive.

Another object of my invention is to apply adhesive to a piece of material, an edge or edges of said piece of material being left free from said adhesive. The advantage of this is that when pressure is applied to the piece of 35 material to cause it to be affixed to another piece of material, the adhesive will not spread beyond the area desired.

Another object of my invention is to connect a piece of material having a film of adhesive thereon, to a second piece of material, 40 by means of air pressure, so that the pressure which is necessary for connecting the two pieces of material will be uniformly and accurately applied.

45 Another object of my invention is to provide a machine for completing glove blanks or "trunks" which will be wholly automatic save that the operator must feed the blanks into the machine and remove the completed 50 blanks from the machine.

Another object of my invention is to provide a complete semi-automatic machine whereby separate pieces of tape will be cut off from rolls thereof, the separated pieces of tape will then be moved by a pneumatic head 55 operating under suction over a device for applying adhesive, and the pneumatic head will then be operated to place the severed pieces of tape in proper position upon a glove blank, compressed air being then admitted into the 60 pneumatic head to press the severed pieces of tape against the "trunk."

Other objects of my invention will be set forth in the following description and drawings which illustrate a preferred embodiment thereof, it being understood that the above general statement of the objects of my invention is intended to generally explain the same and not to limit it in any manner.

Fig. 1 is a plan view of a machine by means 70 of which the improved method can be carried out.

Fig. 2 is a front elevation of the machine at the feeding end.

Fig. 3 is a side elevation showing the right-hand side of the machine.

Fig. 4 is a section on the line 4—4 of Fig. 1.

Fig. 5 is a view of some of the parts shown in Fig. 4, these parts being shown in a different position.

Fig. 6 is a view of some of the parts shown in Figs. 4 and 5, the parts being shown in a third position.

Fig. 7 is a detail of the clutch.

Fig. 10 is a detail view of the mechanism for regulating the vertical movement of the pneumatic head.

Fig. 11 is a detail view, partially in section, showing the tape feeding and cutting mechanism.

Fig. 12 is a side elevation, partially in section, of the tape feeding device.

Fig. 13 is a plan view of the device shown in Fig. 12.

Fig. 14 is a sectional view on the line 14—14 of Fig. 12.

Fig. 15 is a detail plan view of the front end of a part of the tape feeding device.

Fig. 16 is a detail plan view showing the feed dog for feeding the tape.

Fig. 17 is a view of the glove blank showing the reinforcing pieces in proper position.

Fig. 18 is a diagrammatic view of the electric circuit and switch means employed.

Fig. 19 is a detail view showing the switch means utilized.

The machine is provided with a frame 1 having bearings in which a main power shaft 2 is mounted. The power shaft 2 is provided with a clutch device comprising a loose pulley 4 to which a belt 5 is connected. As shown in Fig. 2, the main power shaft 2 is also provided with a hand-wheel 3 for use in temporarily actuating the machine in order to adjust it, or test it, etc.

As also shown in Fig. 2, the clutch device is operated by a treadle 6 connected to a link 7, which is connected to the bell crank lever 8 pivoted at 9 to the frame of the machine. The arm 8a of the lever 8 is connected to the clutch control pin 10. The clutch utilized for connecting the loose pulley 4 to the main power shaft 2 may be of any suitable type and the details thereof are shown in Fig. 7. The main shaft 2 is provided with a collar 11 which turns therewith, and this collar 11 is provided with a pawl 12 pivoted thereto. The said pawl 12 is urged to its outer position by means of a compression spring 14.

As shown in Fig. 7, the loose pulley 4 is provided with internal teeth 15. When the pawl 12 engages said internal teeth 15, the pulley 4 and the shaft 2 turn in unison. When the pulley 4 has turned approximately a full revolution, the pin 10 engages the pawl 12 and pushes it inwardly so that it releases the internal teeth 15. This permits the pulley 4 to turn freely while the shaft 2 remains stationary. By pressing the treadle 6 so as to move the clutch pin 10 in a direction perpendicular to the plane of the paper in Fig. 7, the pawl 12 is released to again engage the teeth 15. Hence, when the operator presses upon the treadle 6 and then releases the same, the shaft 2 is caused to turn for approximately a full revolution and it is then released. As shown in Fig. 2, the main shaft 2 is provided with a bevel gear 16 which meshes with a bevel gear 17 mounted on the transverse shaft 18. As shown more particularly in Fig. 3, the shaft 18 is the main cam shaft of the machine.

As shown in Fig. 1, a wide strip of tape T and a narrow strip of tape Ta are fed into the machine. The wide piece of tape is cut into pieces to form the button or snap fastener reinforcement for the slit of the glove blank 100. Fig. 17 shows one of these pieces which is identified by the reference numeral 101. The pieces which are cut from the narrow tape Ta form slit reinforcements 102. If

desired, these slit reinforcements 102 may be cut so as to have recesses which are aligned with the slit 103 of the blank. The use of such a recess in the reinforcement 102 is well known. Since the mechanisms for feeding the tape T and the tape Ta are identical, only one of them is illustrated in detail in Fig. 11. This shows the strip of tape T wound into a roll R on a spool or the like, which is mounted upon a suitable shaft supported in a bracket 75 21 which is either mounted adjacent to or is suitably connected to the frame of the machine. The tape T passes through a feed box 22. The details of the said feed box 22, and of the appurtenant parts, are shown in Figs. 12-16 inclusive. The feed box 22 is provided with a support 23 for the tape, said support 23 being connected in any suitable manner to the feed box 22, so that there is no relative movement between the support 23 and the feed box 22. As shown in Fig. 13, this stationary member 23 is provided with a stationary spring tongue 23a. Hence, the teeth 24 of the feed dog 24a can project above the said tongue 23a on both sides thereof. The feed dog 24a is pivotally connected at 25 to a slide 26, which is slidably mounted in the feed box 22. The feed dog 24a is provided with an extension 27 which serves to manipulate the same. The slide 26 is guided to slide in suitable position within the feed box 22 by means of the blade spring 28 which is connected to a side wall of the box 22. The free end of the blade spring 28 extends through a recess in said side wall so that said free end presses against the slide 26.

As shown in Fig. 11, the extension 27 of the feed dog 24a is connected to a link 29 which is connected to a lever 30 pivotally connected to the frame of the machine at 31. Said lever 30 has a roller 32 which cooperates with a cam 33 mounted upon the second cam shaft 34. The turning of the cam 33 causes the lever 30 to rock back and forth so that the feed dog 24a is reciprocated, and is also moved up and down so that the teeth 24 engage the tape on the forward feeding movement, and release the tape upon the backward stroke of the feed dog 24a. The bottom of the feed box 22 is slotted so as to permit the extension 27 of the feed dog 24a to move up and down and to also slide back and forth.

As shown in Fig. 12, for example, the extension 27 is close to the adjacent end of the slide 26, so that the feed dog 24a is normally held in such position that its teeth 24 are close to, but do not engage the tape T. When the lever 30 is turned in the clockwise direction, this causes the feed dog 24a to be tilted upwardly and to be also moved forward so that it operates to feed the tape T. When the feed lever 30 is turned in the opposite direction, the feed dog 24a is permitted to tilt downwardly to an extent sufficient to cause its teeth 24 to release the tape T. It 130

is to be understood that any suitable spring can be used for keeping the roller 32 of the lever 30 in constant engagement with the cam 33, such spring not being shown in the drawings as in itself, it is old and well known.

5 A similar feed dog construction is utilized for feeding the narrow tape Ta so that both tapes T and Ta are fed simultaneously and equally.

10 As shown in Fig. 1, the respective feed boxes 22 for the tapes are parallel to each other and said feed boxes 22 may be adjustable so that the distance between them can be varied. This makes it possible to vary the spacing between the members 101 and 102 of the blank 100. The tapes T and Ta are fed forwardly so that their free ends rest upon the cutting table 35. The pneumatic head P is then caused to descend so as to clamp the free ends of the said tapes in position upon said table 35 so that the cutting mechanism can then operate to sever pieces of tape corresponding to the members 101 and 102. One of the cutting devices employed is shown in Fig. 11, it being understood that the construction, operation and movement of the other cutting device is similar since both cutting devices are operated by the same means.

15 20 As shown in Fig. 11, the knife 36 is adjustably connected to the holder 37 by means of set screws 38 which pass through slots in the knife 36. The holder 37 is provided with an extension 39.

25 30 As shown in Fig. 5, the extension 39 is mounted upon a rock shaft 37a and said extension 39 is pivotally connected at 39a to a link 39b which is slidably mounted on the shaft 34. Said link 39b is provided with a roller 39c which cooperates with cam 39d, which is mounted on said shaft 34. It is to be understood that both knives are mounted upon and are actuated by the same rock shaft. The action of said knives is clearly shown in

35 40 45 Fig. 5.

As shown in Fig. 3, the pneumatic head P is connected to two lines of hose 84 and 84'. One of these hose lines is connected to a vacuum pump or the like, for producing suction and the other hose line is connected to a suitable pump or the like for supplying air under pressure. When a vacuum is created in the suction head P, it serves to firmly hold the severed pieces of tape to its perforated under face which is shown in Fig. 9. When compressed air is supplied to the pneumatic head P this causes the pieces of tape to be applied with suitable pressure to the slit 103 of the blank 100. The pressure is utilized after the adhesive has been supplied to the under-faces of the severed pieces of tape. As shown in Fig. 3, the shaft 34 is provided with a sprocket 40 which is driven by means of chain 41 and sprocket 42 located on the transverse shaft 18.

As shown in Fig. 5, the pneumatic head P is suitably connected to a bar 43 which is pivotally connected at 44 to an upright 45 which is rigidly connected to a slideable bar 46. Said slideable bar 46 moves in bearings 47.

5 As shown in Figs. 2 and 10, the pneumatic head P is clamped into position by means of clamping bars 52 which are connected to the pivoted bar 43 by means of screws 53.

10 15 As shown in Fig. 10, one side of the pivoted bar 43 is connected to a U-shaped member 48 which is provided with a pin 49 connected to slide 50. Said slide 50 moves in the guide bar 51.

20 25 30 35 40 45 50 55 60 65 70 75 80 85 90 95 As shown in Fig. 4, an arm 55, whose length can be adjusted by nut member 55a, is pivotally connected to the bar 46 at 54. As shown in Fig. 5, the arm 55 is pivotally connected at 56 to the lever 57 which is pivotally connected at 58 to the frame of the machine. The lever 58 is pivotally connected at 59 to a slotted arm 60 which slides upon the transverse main cam shaft 18. Said arm 60 is provided with a roller 61 which fits in the cam groove 62 of the cam 63, which is mounted on the shaft 18. The guide bar 51 is pivotally connected at 64 to the frame of the machine and it may be provided with a counterweight 65 to balance the weight of the pneumatic head P. Likewise, the pivoted guide bar 51 is guided in its up and down movement between two uprights 68 forming part of the frame of the machine.

20 25 30 35 40 45 50 55 60 65 70 75 80 85 90 95 100 105 A link 66 is pivotally connected at 67 to the pivoted guide bar 51 and this link 66 is pivotally connected at 70 to a lever 71 which is pivotally connected at 72 to the frame of the machine. Said lever 71 is provided with a cam roller 73 which operates in the cam groove of a cam 74, which is mounted upon the shaft 18.

110 Hence, the pneumatic head P is caused to slide back and forth and to also move up and down, the movement thereof being indicated in dotted lines in Fig. 6.

115 The up and down component of the movement thus illustrated in Fig. 6 is to cause the adhesive to be properly applied to the under face of the pieces of tape severed from T and Ta. The adhesive which is applied to the severed pieces of tape is preferably a quick drying rubber cement. This cement is applied to the severed pieces of tape by means of a well known mechanism which requires only 120 general illustration in the drawings. The thick rubber cement is held in a casing 75 provided with a knurled applying roller 76.

125 As shown in Fig. 4, for example, the casing 75 is provided with a shaft 77 having a bevel gear 78 driven by bevel gear 79 on shaft 80 which is driven by belt 81 mounted on the pulley 4.

130 The device operates to cause a thin film of the adhesive to continuously cover the

roller 76 which is mounted on a shaft having a pulley connected by a belt 76a to a similar pulley on the shaft 77.

The vertical or up and down movement of the pneumatic head P is designed to prevent the adhesive from being applied to the front edge or to the rear edge of each severed piece of tape. That is, the film of adhesive which is applied to the under face of each piece of tape, is slightly spaced from the front edge and from the rear edge thereof. It would not be departing from my invention if the film of adhesive were only spaced from one of the edges of the piece of tape, but I prefer to have it spaced both from the front edge and from the rear edge. Since rubber cement is thick, a globule thereof tends to form upon the severed piece of tape when it is pulled away from the applying roller. This excess of adhesive would tend to spread out beyond the edges of the piece of tape, when it was finally applied to the blank. As this would be highly objectionable, it is an important feature of my invention to confine the film of adhesive within the edges (or within a sufficient number of edges) of each severed piece of tape so that when the piece of tape is finally pasted into position, the film of adhesive does not extend beyond the edges thereof.

The glove blanks to be operated upon are placed upon the movable worktable 82 which is slidably mounted in guides 83 connected to the frame of the machine. This table 82 is reciprocated towards and away from the operator.

As shown in Fig. 3, said table 82 has a link 84 pivotally connected to the underside thereof. The link 84 is pivotally connected at 85 to a lever 86 which is pivotally connected at 87 to the frame of the machine. Said lever 86 has a roller 88 which operates in the cam groove of a cam 89 mounted upon the main shaft 2.

As shown in Fig. 1, the guide plate 83a which has the guide flanges 83, has the rear end thereof cut out so that the severed pieces of tape can contact with the roller 76.

The hose line 84 of the pneumatic head P may be designated for convenience, as the suction line, and the hose line 84' may be designated as the pressure line.

The valve for controlling the admission and cut-off of air under pressure is of any suitable type, and it is slidably mounted in the casing 86b, and it is operated by means of a solenoid which is not shown, as solenoid operated valves are in themselves old and well known and form no part of my invention. When the pipes 87b and 88b communicate with each other, air under pressure is supplied to the hose 84'. The valve for controlling the suction of air through the head P is similar type and it is mounted in a casing 86a. Said valve provides or prevents communication between the pipes 87c

and 88c. It is understood that the hose lines 84 and 84' may be connected to the pipes 87c and 87b and that the pipe 88c may be connected to a vacuum pump or the like, and that the pipe 88b may be connected to a pressure pump or the like. The electric control for the solenoids in the casings 86a and 86b is diagrammatically shown in Figs. 18 and 19. The switch control for the solenoid in casing 86b comprises a pair of levers 92 and 92a provided with rollers at their upper ends. The switch disk 90 is preferably made of wood or other insulating material and it is provided with a short metal strip 95 and a long metal strip 93 which are laterally spaced from each other. The switch control for the solenoid in casing 86a comprises a pair of levers 91 and 91a having rollers adapted to contact with the metal strip 93. While two disks 90 are shown in Fig. 18, this is merely for the sake of clearness because the switch roller comprises a single disk 90 made of insulating material and having a short metal strip 95 at one side adapted to cooperate with the levers 92 and 92a, and having a long metal strip 93 on the other side adapted to cooperate with the levers 91 and 91a. It is clear that when the levers 92 and 92a contact with the short metal strip 95, that air under pressure is supplied to the pneumatic head. Likewise, when the levers 91 and 91a contact with the long metal strip 93, suction is applied to the pneumatic head P.

The complete operation of my method and my machine is as follows:

The operator suitably adjusts the boxes 22 so that they are properly spaced from each other corresponding to the desired spacing for the members 101 and 102. At this point the movable worktable 82 is in its outer position. The operator then places a blank in suitable position upon the movable worktable 82 and then presses upon the treadle 6. This operates the clutch so that the pulley 4 is connected to the main shaft 2. The feed dogs 24a then operate to forwardly feed the tapes T and Ta until their free ends rest upon the cutting table 35. The pneumatic head P then descends and suction may be created at this point in the pneumatic head P so as to firmly hold the free ends of the tapes T and Ta in position, although the pressure with which the pneumatic head P is forced down, would be sufficient for this purpose.

The knives 36 are then operated to sever the ends of the tapes T and Ta. Suction must be applied at this point to the pneumatic head P. The pneumatic head P is then raised above the worktable 82 and it is moved laterally, its path of movement having a vertical component so that each of the pieces of tape is supplied with a thin film of rubber cement at its underside, without any excess adhesive being taken up. The pneumatic head P is finally moved to the left-hand position indi-

cated in dotted lines in Fig. 6, the worktable 82 being moved inwardly so as to present the blank in proper position. The pneumatic head P is then caused to descend and when the pieces of tape are pressed against the blank, the suction is cut off from the pneumatic head P and air under pressure is applied thereto. The compressed air forces the pieces of tape evenly and smoothly against the blank. Likewise, the suction causes a certain amount of air to pass around or through the severed pieces of tape, and the air under pressure passes around or through the severed pieces of tape so that the adhesive is very quickly dried and set.

The air pressure causes the film of adhesive to move substantially to the edges of the severed pieces of tape so that the members 101 and 102 are properly pasted into position.

The clutch is automatically tripped after the slideable worktable 82 has moved to its outer position. At this time, the pneumatic head P is at the full-line position illustrated in Fig. 6 so that the machine is ready for another operation. The cutting knives may have any suitable shape so as to give any desired shape to the members 101 and 102, it being understood that the rectangular shape illustrated in Fig. 17 is merely illustrative.

As shown in Fig. 8, tension springs S are utilized for holding the respective levers 91 and 92 so that they will contact with the respective metal strips on the switch roller 90.

As shown in Fig. 9, I prefer that the severed pieces of tape should not completely obstruct the perforated bottom face of the pneumatic head P. Hence when suction is applied, air can pass around the severed pieces of tape. Likewise, when air under pressure is applied to the pneumatic head P, it can pass out of the said pneumatic head P.

However, it would not be departing from my invention if the perforations in the pneumatic head P were so arranged so that they were substantially closed by the severed pieces of tape.

While I have shown a completely organized semi-automatic machine, I do not wish to be limited to the complete machine described, as many of the subcombinations thereof could be separately utilized whenever it is desired to connect one piece of material to another by means of an adhesive.

For example, it can be readily seen that the pneumatic head P could be connected to a single hose line with suitable valves and control means for connecting this single hose line to vacuum producing means, and to a source of air under pressure.

Likewise, while I have shown the piece of tape being moved towards and across and away from the adhesive-applying means 76,

I am not to be limited to this particular movement as the essential feature of this portion of my invention is to produce a relative movement between the piece of material and the adhesive-applying means which shall prevent an excess of adhesive from being supplied to the piece of material. Likewise, it is well known to provide tape with a layer of dry adhesive and to render said adhesive operative by moistening the same. It therefore would not be departing from my invention if the adhesive-applying means were replaced by moistening means or the like across which a piece of tape having a layer of dry adhesive could be moved, in order to moisten said adhesive and render the same operative.

Generally speaking, while I have shown a preferred embodiment of my invention, it is clear that numerous changes and omissions could be made without departing from the spirit of my invention.

I claim:

1. In a machine for connecting a first piece of material to a second piece of material by means of an adhesive, a pneumatic head, means adapted to create a vacuum in said head, means adapted to supply air under pressure to said head, first control means adapted to control said vacuum producing means, second control means adapted to control said means for supplying air under pressure, operating mechanism adapted to apply the said pneumatic head to the first piece of material, said first control means being then operative to enable a vacuum to be produced in said head so that the first piece of material clings to said head, adhesive-supplying means, said operating mechanism being adapted to cause the piece of material clinging to said pneumatic head to contact with said adhesive-supplying means so as to produce a film of adhesive upon the exposed face of said first piece of material, said operating means being then adapted to cause said first piece of material to contact with the second piece of material, said first control means being adapted to cause said vacuum producing means to then become inoperative, said second control means being adapted to then cause air under pressure to be supplied to said pneumatic head.

2. In a machine for causing a first piece of material to be connected to a second piece of material by means of an adhesive, the subcombination of adhesive-applying mechanism, a carrier adapted to carry the first piece of material towards and across and away from said adhesive-applying mechanism so that the first piece of material has one of its faces provided with a film of adhesive, said carrier being then adapted to press the first piece of material against the second piece of material.

3. In a machine for causing a first piece of material to be connected to a second piece

- of material by means of an adhesive, the sub-combination of adhesive-applying mechanism, a pneumatic head having a suction line and a pressure line connected thereto, and 5 mechanism adapted to actuate said pneumatic head towards and away from and also across said adhesive-applying mechanism.
4. In a machine for causing a first piece 10 of material to be connected to a second piece of material by means of an adhesive, the sub-combination of a slidable frame having a first bar pivotally connected thereto, a pneumatic head connected to said first bar, mechanism adapted to reciprocate said sliding frame including said first bar, a second pivoted bar 15 connected to the frame of the machine, a slide connecting said first bar to said second pivoted bar, and means adapted to rock said second pivoted bar so as to impart a reciprocating movement to the pneumatic head in a direction perpendicular to the direction of movement of said sliding frame.
5. In a machine for causing a first piece 20 of material to be connected to a second piece of material by means of an adhesive, the sub-combination of a slidable frame having a first bar pivotally connected thereto, a carrier for a piece of material connected to said first bar, mechanism adapted to reciprocate said 25 sliding frame including said first bar, a second pivoted bar connected to the frame of the machine, a slide connecting said first bar to said second pivoted bar, and means adapted 30 to rock said second pivoted bar so as to impart a reciprocating movement to the carrier for a piece of material in a direction perpendicular to the direction of movement of said 35 sliding frame.
6. In a machine for causing a first piece 40 of material to be connected to a second piece of material by means of an adhesive, the sub-combination of a movable worktable upon which a first piece of material can be placed, mechanism adapted to actuate said movable 45 worktable, a carrier adapted to hold a second piece of material and operating mechanism for said carrier adapted to move it laterally with respect to said worktable and to also move it in a direction towards and away from 50 said worktable.
7. In a machine for causing a first piece of material to be connected to a second piece of material by means of an adhesive, tape feeding mechanism adapted to feed tape to the 55 said machine, cutting mechanism adapted to sever the said tape into predetermined lengths, a pneumatic head adapted to be connected to means for producing a vacuum and also adapted to be connected to means for 60 supplying air under pressure thereto, first control means for said vacuum-producing means, second control means for said means for supplying air under pressure, operating mechanism connected to said pneumatic head, said operating mechanism being adapt- 65 ed to apply said pneumatic head to the severed tape, said first control means being then operative to cause suction to be produced in said pneumatic head to cause the severed tape to cling thereto, adhesive-applying 70 mechanism, said operating means being adapted to cause the pneumatic head together with the piece of tape clinging thereto, to move towards and across and away from the said adhesive-applying mechanism so that a film of adhesive is formed on the exposed face of the severed tape, a movable worktable adapted to hold the second piece of material, means adapted to actuate said movable work-table so that the second piece of material thereon is moved vertically below the pneumatic head, said operating means being then effective to lower the pneumatic head to cause the severed tape to be pressed against the first piece of material, said second control 75 means being then adapted to cause air under pressure to be supplied to the said pneumatic head.
8. In a machine for causing a first piece 80 of material to be connected to a second piece of material by means of an adhesive, a pneumatic head having a perforated underface, said pneumatic head being adapted to be connected to vacuum-producing means and being also adapted to be connected to means for 85 supplying air under pressure, control means for said vacuum-producing means and control means for said means for supplying air under pressure, and means adapted to feed a piece of material to said perforated face to 90 cling thereto, said perforated face having holes which are then free from contact with said severed piece of material, adhesive-applying mechanism and operating means for said pneumatic head adapted to move it 95 towards and across and away from said adhesive-applying mechanism.
- In testimony whereof I affix my signature.
